(57) CLAIM

The ornamental design for a paper sheet as shown and described.

DESCRIPTION

FIG. 1 is a perspective view of a paper sheet according to our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top view thereof; and,

FIG. 7 is a bottom view thereof.

The dot-dash broken lines within FIGS. 1 and 2 denote the boundaries of the claim and form no part thereof. The areas and broken lines outside of the boundary depict portions of the paper sheet that form no part of the claimed design.

In the figures without dot-dash broken lines, the broken lines form no part of the claimed design. The broken lines within the boundary, shown in FIGS. 1 and 2 depict portions of the paper sheet that form part of the claimed design.

The word "Charmin" is a registered trademark of The Procter & Gamble Company.
